COMBINED CONTAINER AND ARTIFICIAL FINGERNAILS

Eric V. Aylott, 58-60 Bridge Road E.,
Welwyn Garden City, England

Filed Sept. 11, 1968, Ser. No. 13,495

Claims priority, application Great Britain July 16, 1968

Term of patent 7 years

Int. Cl. D9—04

U.S. Cl. D9—187

FIG. 1.

FIG. 2.

FIG. 1 is a top perspective view of a combined container and artificial fingernails showing new design in an open condition;

FIG. 2 is a section taken on line 2—2 of FIG. 1.
The top, bottom and sides of the container are of flat planar configuration.

The diagonal shade lines in FIG. 1 represent a transparent cover over the artificial fingernails at the front of the container tray.

I claim:

The ornamental design for a combined container and artificial fingernails, as shown and described.
